UNITED STATES PATENT OFFICE.

ABRAHAM SUSSMAN, OF NEW YORK, N. Y.

DESIGN FOR FRINGE.

Application filed June 7, 1914. Serial No. 9,822. Term of patent 14 years.

To all whom it may concern:

Be it known that I, ABRAHAM SUSSMAN, a citizen of the United States, and a resident of the city of New York, borough of Manhattan, in the county and State of New York, have invented a new, original, and ornamental Design for Fringe, of which the following is a specification.

Reference is to be had to the accompanying drawing in which the figure is a view in elevation of a fringe constructed in accordance with the present invention.

I claim—

The ornamental design for fringe as shown.

ABRAHAM SUSSMAN.
